(57) CLAIM

The ornamental design for a litter container, as shown and described.

DESCRIPTION

FIG. 1 is a top perspective view of a litter container in accordance with our new design;

FIG. 2 is a bottom perspective view thereof;

FIG. 3 is a top view thereof;

FIG. 4 is a bottom view thereof;

FIG. 5 is a left side view thereof;

FIG. 6 is a front view thereof; and,

FIG. 7 is a back view thereof.

The broken lines depict environmental subject matter, are for illustration only, and form no part of the claimed design.
